UNITED STATES PATENT OFFICE.

WILLIAM W. BOLLES, OF TOLEDO, OHIO.

ADJUSTABLE WINDOW-CORNICE.

SPECIFICATION forming part of Letters Patent No. 223,699, dated January 20, 1880.

Application filed July 1, 1879.

To all whom it may concern:

Be it known that I, WILLIAM W. BOLLES, of Toledo, in the county of Lucas and State of Ohio, have invented a new and Improved Adjustable Window-Cornice, of which the following is a specification.

Figure 1 is a front elevation of the cornice. Fig. 2 is a sectional elevation on line xx , Fig. 1. Fig. 3 is a sectional elevation on line yy , Fig. 1.

Similar letters of reference indicate corresponding parts.

The object of this invention is to furnish an ornamental window-cornice that without alteration can be adjusted to a window of any width.

The invention consists of an ornamental piece of molding, on which are secured thicker and grooved or channeled edges, and on each end of which is rigidly fixed a mortised truss, the whole forming the center-piece of the cornice. The side extensions of the cornice consist of two pieces of molding that are made to slide in the mortises of the trusses and the channels or grooves of the edge strips, and meet behind the center-piece. The mortises in the trusses conform in their general outlines with the outlines of the moldings, and the trusses are also cut through from their tops to the mortises, in order to make them so elastic that they will not bind on the sliding cornice-extensions.

In the drawings, A represents the front piece, which may be of any desired length, as the length of this determines the range of adjustability of the cornice.

B B' are the grooved edge pieces or top and bottom pieces, that may be made as ornamental as desired, while the front piece should conform in outline with the side extensions.

C are the trusses with the vertical cut a' in them, that may be drawn together by the screws b' , and that are provided with the mortises c' , that extend through them.

D are the side-extension moldings, that slide 45 in the mortises c' and in the grooves d' of the top and bottom pieces, and by these are held in place; or these grooves may be dispensed with and the ends of the extensions be steadied by slotting them and passing thumb-screws 50 through the slots and into the back of the front piece.

I am aware that adjustable window-cornices are not new, nor elastic mortised trusses; and I am also aware that cornices have been made 55 of two like pieces that slide upon each other, to an end of each of which is secured a mortised bracket or truss whose mortise conforms in its outlines with the surface-lines of the moldings; but this style of cornice is objectionable in a measure, because the two halves, though parallel with each other, are not in the same plane, and hence present an irregular appearance. I do not therefore claim a cornice composed of two like parts sliding upon each 60 other; but,

Having thus fully described my invention, I claim as new and desire to secure by Letters Patent—

The within-described window-cornice, consisting of front piece, A, grooved top and bottom pieces, B B', mortised trusses C, provided with vertical cut a' , and side-extension moldings D, constructed and arranged substantially as herein shown and described.

WM. W. BOLLES.
